CIRCULATING HEATER

Filed April 13, 1936

UNITED STATES PATENT OFFICE

100,113

DESIGN FOR A CIRCULATING HEATER

John Balderston Miller and William Porter Biddle, Jr., Knoxville, Tenn., assignors to Knox Stove Works, Knoxville, Tenn., a corporation of Tennessee

Application April 13, 1936, Serial No. 62,107

Term of patent 14 years

To all whom it may concern:

Be it known that we, John Balderston Miller and William Porter Biddle, Jr., citizens of the United States, residing at Knoxville, county of Knox, and State of Tennessee, have invented a new, original, and ornamental Design for a Circulating Heater, of which the following is the specification, reference being had to the accompanying drawing, forming part thereof.

In the drawing:—

The figure is a perspective view of the circulating heater, showing our new design; the other side of the heater is substantially like the side shown.

We claim:—

The ornamental design for a circulating heater, as shown and described.

JOHN BALDERSTON MILLER.
WILLIAM PORTER BIDDLE, JR.
